UNITED STATES PATENT OFFICE.

GEORGE E. MCNEAL, OF CLEVELAND, OHIO.

PARTITION STRUCTURE.

1,426,584.

Specification of Letters Patent. Patented Aug. 22, 1922.

Application filed November 8, 1921. Serial No. 513,709.

To all whom it may concern:

Be it known that I, GEORGE E. MCNEAL, a citizen of the United States, residing at Cleveland, in the county of Cuyahoga and 5 State of Ohio, have invented certain new and useful Improvements in Partition Structures, of which the following is a specification.

My invention relates to improvements in 10 partition structures, and more particularly to that class or type in which individually complete filling units or sections are combined or connected to form one continuous partition, the units or sections being made 15 interchangeable at the factory and being so constructed and arranged as to be readily erected at the desired place by persons not necessarily having any great degree of skill, and which may be taken down and shifted 20 if desired to other locations and in other combinations and arrangements.

The primary object of the invention is to provide a generally improved sectional partition of the class indicated which will be 25 exceedingly simple in construction, cheap of manufacture, and efficient in use.

A further and very important object is the provision of individually complete interchangeable partition units or sections 30 having conductor receiving and concealing chair-rails and baseboards, together with improved unit spacing and coupling or connecting members interposed between the said chair-rails and baseboards and spacing 35 said partition units apart and bridging said space, forming a conductor receiving space between said units adapted to communicate with the conductor receiving and concealing portions of said chair-rails and base- 40 boards.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a 50 part of this specification, Figure 1 is a fragmentary side elevation of a partition structure constructed in accordance with this invention, one of the unit spacing and coupling members being removed for the purpose of clearer illustration of the parts.

Fig. 2, a fragmentary perspective view of 55 the adjacent ends of a pair of partition

sections or units in disassembled position preparatory to being brought together and connected, certain parts being broken away and shown in section for the purpose of 60 clearer illustration of the parts.

Fig. 3, a transverse or cross sectional view taken on line 3-3 of Fig. 1.

Fig. 4, an enlarged fragmentary cross sectional view taken on line 4-4 of Fig. 1. 65

Fig. 5, a similar view taken on line 5-5 of Fig. 1.

Fig. 6, a similar view taken on line 6-6 of Fig. 1.

Similar numerals of reference designate 70 like parts throughout all the figures of the drawings.

The improved partition is made up of a suitable number of individually complete 75 partition sections or units constructed and connected substantially as shown in one of its embodiments in the accompanying drawings and hereinafter referred to.

The sections or units may be constructed 80 in any suitable and convenient manner with any desired arrangement of panelling according to the particular type or ornamentation desired. In the present instance, I have shown each section as comprising an opaque panel 1, surmounted by a sash made 85 up of the stiles 1^a, receiving the rails, 1^b. The sash is adapted to contain a panel or section of glass 1^c, or other transparent or translucent material.

As a means of providing the panelled sections or units with suitable conductor receiving and concealing portions or openings, suitable chair-rails 1^d, and base or washboards 1^e, are provided on opposite sides of the intermediate and base portions 95 of the sections as shown most clearly in Fig. 2 of the drawings.

In the present instance, the conductor receiving and concealing portions or openings 1^f, are formed by means of under channelled 100 portions in the rails and boards and, if desired, the adjacent wall or panel of the section may be provided with a companion or registering panels or grooves 1^g, intersecting the edges of the sections or units as shown 105 most clearly in Figs. 2 and 6 of the drawings for the purpose of communicating with the vertical intervening conductor receiving and concealing openings formed as herein-after described. If desired, the unit spacing and coupling members or bars herein-after referred to and interposed between the 110

chair-rails and base boards may likewise be provided with registering channels or grooves for affording access from said chair-rails to said intervening openings between 5 the adjacent sections or units.

- As a means of coupling or connecting the panelled units or sections together when set up, and particularly as a means of spacing the adjacent or contiguous edges thereof,
- 10 a suitable distance apart to form vertical conductor receiving and concealing passages or openings adapted to intersect the openings or passages 1^f, in the chair-rails and baseboards above referred to, suitable unit spacing and coupling members 2 are provided, said spacing and coupling members 2, in the present instance, comprising vertically extending post forming bars secured to the marginal edges of the sections and
  - 15 interposed between the ends of the chair-rails and baseboards, the latter terminating short of the vertical edges of the panelled sections and the dimensions of the parts being such as to space the edges of the sections and parts to form an intervening space 2^a providing a vertically extending conductor receiving and concealing passage.
  - 20
  - 25

When the sections or units are completed at the factory the section spacing and coupling bars 2, may be attached to diagonally opposite sides by means of suitable attaching elements 2^b, such as screws or the like, so that when assembling the adjacent or contiguous edges may be readily brought together in the manner suggested in Fig. 2 of the drawings, after which the opposite edges of the coupling bars and panels may be secured together, the vertical unit spacing and coupling members 2 thereby bridging the intervening space 2^a between the sections adapted to communicate with the horizontally extending conductor receiving openings of the rails 1^b and boards 1^e, as shown most clearly in Figs. 5 and 6 of the drawings.

- 30
- 35
- 40
- 45
- 50

The post forming and unit spacing and connecting members 2 are preferably of the same thickness as the chair-rails 1^b and baseboards 1^e, so as to extend flush therewith, as shown most clearly in Figs. 2 and 3 of the drawings.

When the partition sections or units are thus brought into assembled relation and coupled together, as above referred to, a top or cornice rail 3, is adapted to be mounted above and extend over a plurality of the connected sections or units, said top or cornice rail 3, in the present instance, being provided with oppositely arranged grooves or channels 3^a, adapted to receive and fit over the marginal edges of the rails 1^b of the sash. The top or cornice rail 3 is adapted to receive and support on its opposite side suitable crown or cornice mouldings 3^b, the grooves 3^a at the top of the cornice 65 rail 3, being admirably adapted to receive

and form a seat for the edges of a superposed rail or panel (not shown) should it be desired to add to the height of the partition or to extend it to the ceiling.

It will be seen also that the top or channelled portions of the crown mouldings 3^b and the top or cornice rail 3 are admirably adapted to receive a conductor cord 4, along its length, said cord being adapted to enter any desired vertical intervening space 2^a, by 75 boring out an opening 3^c immediately above the desired intervening space, as shown most clearly in Fig. 1 of the drawings.

Having thus described one of the embodiments of my invention, without having attempted to set forth all the forms in which it may be made, or all the modes of its use, what I claim and desire to secure by Letters Patent is:

1. A partition structure, comprising individually complete filling units including under channelled chair-rails and baseboards forming horizontal conductor receiving openings, overlapping vertical post forming unit connecting members abutting against 90 said chair-rails and baseboards and spacing said filling units apart forming intervening vertical conductor receiving openings intersecting said horizontal conductor receiving openings.

2. In a partition structure, the combination with individually complete section units including chair-rails and baseboards terminating short of the contiguous edges of said units, vertical unit spacing coupling 100 bars disposed between the end of said chair-rails and baseboards and spacing the edges of said units apart forming intervening conductor receiving spaces, and a top rail extending along the upper edges of said 105 units when coupled together.

3. A partition structure, comprising filling panel sections, chair-rails and baseboards, said baseboards being provided with conductor receiving portions, and vertical panel 110 section spacing and connecting bars between the ends of said chair-rails and baseboards whereby said panel sections are spaced apart forming covered intervening spaces for receiving and concealing conductors adapted 115 to communicate with said conductor receiving portions of said baseboards.

4. A partition structure, comprising individually complete panelled section units including conductor receiving and concealing baseboards arranged on said units and terminating short of the contiguous vertical edges thereof, vertical unit spacing and coupling members interposed between said chair-rails and baseboards and spacing said 120 section units apart and bridging said space forming a conductor receiving space there between intersecting said conductor receiving and concealing baseboards.

5. A partition structure, comprising 125

panelled section units including chair-rails and baseboards provided with conductor receiving spaces, overlapping vertical post forming unit connecting bars extending between and flush with said chair-rails and baseboards and spacing said panelled section units apart forming intervening vertical conductor receiving spaces intersecting said conductor receiving spaces of said chair-rails and baseboards.

6. A partition structure, comprising individually complete panelled section units including conductor receiving and concealing chair-rails and baseboards arranged on the outer sides of said units and terminating short of the contiguous vertical edges thereof, vertical unit spacing and coupling members interposed between said chair-rails and baseboards and forming a conductor receiving space there between intersecting said conductor receiving and concealing portions formed by said chair-rails and baseboards.

7. A partition structure, comprising filling panel sections, chair-rails and baseboards provided with conductor receiving and concealing portions and terminating short of the vertical edges of said filling panel sections, and vertical panel section

spacing and connecting members fitted between the ends of said chair-rails and baseboards and conjointly with the spaced ends of said panel section formed thereby forming conductor receiving and concealing spaces communicating with said conductor portions of said chair-rails and baseboards.

8. In a partition structure, the combination with individually complete panelled section units including chair-rails and baseboards provided with conductor receiving and concealing openings and terminating short of the contiguous edges of said units, and overlapping vertical unit spacing and coupling bars disposed between the ends of said chair-rails and baseboards and spacing the edges of said units apart forming a conductor receiving opening communicating with said first mentioned conductor receiving and concealing openings, and top rail and crown mouldings extending along and connecting the upper edges of said units when coupled together by said unit spacing and coupling members.

In testimony whereof I have affixed my signature.

GEORGE E. McNEAL.
